RAILWAY TRACK ALIGNER

Bernard Geier, Moscow, Pa., assignor to Railway Track Works Company, Philadelphia, Pa., a corporation of Pennsylvania

Application August 19, 1955, Serial No. 529,469

1 Claim. (Cl. 104—8)

My invention relates to a railway track aligner.

A purpose of my invention is to provide an aligner for railway track that is at once highly effective and comparatively simple and quite economical, both in manufacture and use.

A further purpose of my invention is to provide such an aligner which may with great ease and expedition be shifted to move the railroad track in either sidewise direction, but yet is by no means complicated or expensive.

Further purposes will be found in the specification and the claim.

My invention is illustrated in the drawings by an embodiment chosen from the standpoint of convenience in illustration, satisfactory operation, and clear demonstration of the principles involved.

Figure 1 is a perspective of an embodiment of my invention.

Figure 2 is a view in elevation of a slight variation of this embodiment, having the handle on the opposite side of the casing, with the particular view leaving out a number of things that are part of the actual structure, to wit: the part that is on the carriage is distinguished from the part that contacts the rail and the ground, and also most of the tubing and also the dogs which hold the L-shaped members in place.

Figure 3 is a top plan view of Figure 2, omitting the top end members of the body, the L-shaped members and the nuts thereon.

Figure 4 is a longitudinal section of the hydraulic portion, with the piston rod shown in elevation.

Figure 5 is an enlarged fragmentary view the same as Figure 4, except that the outer walls of the piston rod are shown in section.

Figure 6 is a fragmentary view showing the top of the L-shaped member together with associated nuts.

In the particular embodiment of my invention shown in the drawings, body 10 extends across from rail to rail, and is made up of two parallel horizontal spaced beams 12 and 14, joined at the ends by top end pieces 16 and 17, and lower end piece 18 or abutment member 19. The beams can be in the form of channels facing toward each other, for example. The top end pieces have top portion 20, rod 22 extending across the top near the inside, side pieces 24 (only the nearer of which is shown), and in the top, member 28 with a hole therein to support part of a clamping means to be hereinafter described.

At opposite ends of the structure, axles 36 and 38, respectively, are mounted, one of them for the wheel 40 with the inner flange 42 and smaller outer flange 43, and the other one for the wheel 44 without any flange.

Mounting for the respective axles is provided by lower end piece 18 in the case of axle 36 and abutment member 19 in the other. Each of these has side pieces 50 and 52 respectively, and each has cross pieces, 54 and 56 respectively, in which the axles are mounted, but in abut-

2

ment member 19, the lower part projects to form an abutment 60.

Extending down through the previously mentioned hole in member 28, is clamping means 62, consisting of L-shaped members 64 and adjusting nut 66 with lever rod 68 welded thereto, and locking nut 70. The L-shaped member, which can, for example, be formed of tubing, has a screw thread on top on which the adjusting nut and locking nut are put to fix the point at which its 10 lowermost position will be, and to tighten the entire assembly so that turning the lever rod 68 will turn the L-shaped member. Running from the frame down to a position on the L-shaped member is coil spring 75, which tends to bring the L-shaped member up when free 15 to so move until it reaches the point where collar 77 reaches the hole.

Standing up in the space between the beams is hydraulic mechanism 84. On the outside of this is a casing 86, with two lugs 88 (only the nearer one of which is shown) riding in the respective slots 90 (only the nearer of which is shown). The slots 90 are formed respectively on the bottom of the intermediate portion of each beam by a space between angle 92 and reinforcement 94 on the bottom of the beam, angle 92 being 20 held on at opposite ends by bolts 96.

Inside the casing 86, attached to the top thereof, is hollow piston rod 98 extending down longitudinally and having thereon piston 100. Cooperating with the piston is cylinder 102 which extends up into the casing around 25 the piston and whose ends 104 and 106 together with the side walls form chambers 108 and 110. Hydraulic pressure connections 112 and 114 extending down the interior of the piston rod to opposite sides of the piston provide for admission of hydraulic pressure to these 30 chambers to move the cylinder up or down relatively to the piston. At the lower end of the cylinder is pin 116, to which is attached foot 118 by pivot element 120.

The foot consists of bow member 122, which is a broad channel with its open side downward, in the shape 40 of an arc concave downward with pivot element 120 at the middle of its top, straight members 124 extending in more or less bow-string fashion across the greater part of the bow member to which they are bolted at both ends and end pieces 128 and 130, which are flat 45 pieces of fairly large size, as for example 6 inches longitudinally and 7½ inches across the foot, which are fastened to the ends of the bow piece, as by welding, in such a way as to present a bottom face which is sloping upwardly and outwardly from the rest of the foot 50 at an inclination which is preferably about 19½ degrees.

Lever 136 is pivoted at 138 in the center of the top of one of the beams. Its larger end extends upward to handle 140, while its smaller end extends downward to longitudinal slot 142 toward the end of this end, which 55 surrounds one of the lugs 88 beyond where the lug 88 passes through slot 90 on the bottom of the beam.

The pressure for the chambers 108 and 110 is supplied by way of pump 150 driven by gasoline motor 152, and 60 operated in conjunction with storage tank 154 for hydraulic fluid, all located on carriage portion 156. The pump, motor and tank can be of any suitable standard form adequate to develop the pressure needed, and are therefore shown merely diagrammatically. Pressure of 1800 pounds per square inch is suitable, with a piston 65 area which would develop 10 tons of actual force in the sidewise direction when pushing against the rail. The pressure fluid can be of any suitable kind, such as, for example, hydraulic oil. Suitable control valves (not shown), well known in the art, controlled from control 70 panel 158, can cut the pressure connection off altogether or can direct the pressure fluid through the appropriate line of hose set up 160 to produce pressure in the cham-

ber desired for the particular relative movement desired between piston and cylinder.

The carriage portion 156 is at one side, joined in one unit with the rest of the device as shown and has handles 162 thereon and an additional wheel 164 underneath, to facilitate the handling of the device as a whole.

In operation, the device is set up with wheel 40 on one rail and wheel 44 on the other, abutment 60 abutting on the inside of the latter rail. The L-shaped members are turned by means of lever rods 68 to bring them under the base of the respective rails, after due adjustment of their longitudinal position has been made, if necessary, by means of the adjusting nut 66 and locking nut 70.

The hydraulic power will be applied to expand the hydraulic mechanism and thus force the foot gradually into the ground and over in the direction of the other rail until it gets a firm seating. When a firm seating has been attained, the hydraulic input to the cylinder will be continued at a higher rate, and the casing 86 will push against the body by means of the lugs, together with the side of the hydraulic casing bearing against the rod 22 in the top end piece 16 or 17. The rail will thus be pushed over to put it into perfect alignment. The push delivered by this device is such that it will at the same time permit the weight of the device to bear down on the rail which is being pushed and, along with the weight of rail and tie itself, prevent it from going up out of vertical alignment. If perchance the push should be too great and the rail should be pushed somewhat beyond the point of perfect lateral alignment, the lever can readily be pulled back the other way, after suitable retraction of the cylinder, thus setting the casing in the opposite direction, and the whole process can be repeated in the opposite direction.

We thus have an extremely simple, inexpensive device which nevertheless is very easy to use, requires only a very small crew, and can be shifted from one direction to another with the utmost ease, and is highly effective in doing its job.

When alignment has been completed at one point, the L-shaped members can be removed from under the rail and the whole car moved to the next spot at which work is desired and the alignment process repeated.

In view of my invention and disclosure variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claim.

Having thus described my invention, what I claim as new and desire to secure by Letters Patent is:

A railway track aligner comprising a parallel beam

structure having two horizontal parallel spaced beams, connections between the beams at the ends thereof, axles on said parallel beam structure extending out longitudinally from each end thereof, wheels on the axles, the 5 wheels at one end being flanged on the inside edge and at the other end unflanged, said parallel beam structure having connected thereto an end abutment extending below the beam structure at the end where the wheel is not flanged, and the far edge of said abutment being spaced 10 along the beam from the far edge of the flange a distance equal to the distance between the inner edges of the heads of the rails of a track, L-shaped members mounted on the ends of said structure to pivot about the vertical legs of the L on a vertical axis, the bottom leg of the L 15 in a variable position engaging and gripping the bottom of the base of the rails, walls forming horizontal guideway means along the bottom of the intermediate part of each beam of the structure, an elongated casing extending from above into the space between the beams and 20 having lugs extending into the guideway means to ride therein, a piston rod mounted on the inside of the top end of the casing and extending in a longitudinal direction down in the inside thereof, a piston on the end of the piston rod, a cylinder extending into the casing from below and surrounding the piston and closed at the ends to form hydraulic compartments, a source of hydraulic power connected through valving means to the compartments, a foot having center structure, the top of which 25 is pivoted to the lower end of the cylinder and having two end pieces having flat bottom surfaces outwardly and upwardly inclined at a slope less than 45 degrees, and a lever pivoted to the top of the center to one of the beams and having a long end extending upward and ending 30 in a handle and a short end extending downward and having walls forming a longitudinal slot in the end thereof, said slot receiving one of the lugs of said casing, the lever in one position disposing the casing diagonally directed toward one rail and in another position disposing the casing diagonally directed toward the other rail.
